UNITED STATES PATENT OFFICE.

ADELARD F. MARTEL, OF MONTREAL, QUEBEC, CANADA, ASSIGNOR OF ONE-FOURTH TO CHARLES AUGUSTE MARTEL, OF SAME PLACE.

SEAL-LOCK FOR CARS.

SPECIFICATION forming part of Letters Patent No. 245,645, dated August 16, 1881.

Application filed May 14, 1881. (Model.)

To all whom it may concern:

Be it known that I, ADELARD FRANK MARTEL, of the city of Montreal, in the county of Hochelaga, in the Province of Quebec, Canada, railway-conductor, have invented certain new and useful Improvements in Car Seal-Locks; and I do hereby declare that the following is a full, clear, and exact description of the invention.

10 My invention is an improved car seal-lock, consisting of an automatic lock and seal so arranged that the door of the car is sealed and locked by simply closing the door. It is provided with a shield on one or both sides of the 15 spring-latch, so that when it is locked an instrument cannot be inserted to raise the latch, thus preventing the opening of the door without breaking the seal.

Figure 1 is a side elevation of the car with 20 my improved seal-lock, catch, and shield. Fig. 2 is a front view of the catch. Fig. 3 is a front view of the lock. Fig. 4 is a sectional view of the lock-case, showing the spring-latch; and Fig. 5, a seal detached.

25 A is the car-door, moving in slides, as usual; but when closed its front incases itself into the jamb of the door-frame, so as to allow no opening between the door and door-jamb.

B is the door-jamb, provided with a recess 30 in its whole length to receive the car-door when closed, and to which the catch G is fitted to receive the spring-latch D.

C is the lock-casing, provided with a projecting shield, C', to prevent the introduction 35 of any thin instrument or contrivance to raise the spring-latch D when the door is locked and sealed, and to which the spring-latch D is pivoted at about its center by a hollow shaft, in which is a square or other aperture to receive a key, F, to open it, having its shaft fitted to enter the aperture in the hollow shaft of the spring-latch D, so as to raise it out of the catch G to open the door.

40 E is the seal-case, in which a flat water-proof 45 seal of any description is inserted, covering

the aperture in the hollow shaft, and leaving a portion of itself exposed, on which any required inscription may be placed, so that the car cannot be opened without perforating the seal with the key by inserting it in the aperture of the hollow shaft of the spring-latch D, so as to raise it out of the catch G and open the door, thus showing from inspection whether the seal has been tampered with.

50 F is the key, having a square or other shaped shaft fitted to enter the aperture in the hollow shaft of the spring-latch D.

G is a catch fitted to the door-jamb B of car, to receive the spring-latch D to lock the door.

The sealing of locked cars in an expeditious manner so as to prevent access thereto without leaving some trace of irregularity behind is one of the necessities of the present time. Not only to prevent illegal access thereto, but also to lock and seal the car without 65 undue loss of time, is much to be desired when combined with simplicity of construction and non-liability to get out of repair.

I am aware of seal-locks being used for the purpose of locking cars. Those I do not claim, 70 as I know there are many devices of the kind in use; but

What I do claim as my invention is as follows:

1. The combination of a catch or keeper and 75 a lock provided with a protruding locking bolt or latch, and having its case provided with a shield to cover the protruding portion of said bolt or latch to prevent tampering therewith.

2. In combination with a keeper or catch, a 80 lock having a protruding locking bolt or latch, and having its case provided with a shield to cover the protruding portion of said bolt or latch, and with a seal-passage open at the edge or side of the case, through which the bolt protrudes.

A. F. MARTEL.
